UNITED STATES PATENT OFFICE.

ETHAN I. DODDS, OF AVALON, PENNSYLVANIA, ASSIGNOR TO PRESSED STEEL CAR COMPANY, OF PITTSBURG, PENNSYLVANIA, A CORPORATION OF NEW JERSEY.

BRAKE-BEAM.

SPECIFICATION forming part of Letters Patent No. 777,279, dated December 13, 1904.

Application filed February 23, 1904. Serial No. 194,646. (No model.)

To all whom it may concern:

Be it known that I, ETHAN I. DODDS, of Avalon, Allegheny county, Pennsylvania, have invented a new and useful Brake-Beam, of which the following is a full, clear, and exact description, reference being had to the accompanying drawings, forming part of this specification, in which—

Figure 1 is a plan view showing how the flanged beam is slit preparatory to bending it into the form of a brake-beam. Fig. 2 shows the brake-beam made from the blank illustrated in Fig. 1. Fig. 3 is a plan view of Fig. 2. Fig. 4 is a plan view of a modified construction. Fig. 5 is a vertical section on the line V V of Fig. 3. Fig. 6 is a vertical section on the line VI VI of Fig. 4. Fig. 7 is a view similar to Fig. 5, showing the middle member flanged. Fig. 8 is a view similar to Fig. 2, showing the side members bent away from the middle member.

The purpose of my invention is to provide for the manufacture of brake-beams for cars from flanged metal pieces, such as sections of I-beams or channels, with the least possible waste of material and in such manner as to obtain an article of great strength and rigidity. I make the brake-beam by slitting a flanged beam-section with slits extending longitudinally through its web, so as to afford a middle member and two side members, and then bending the middle member away from the side members in a direction transverse to the plane of the web and accommodating for the shortening of the metal so occasioned, preferably by bending the side members away from the middle member or laterally toward each other.

In Fig. 1, 2 represents a section of the metal beam, which may be an I-beam or a channel-beam, from which my brake-beam is made. It is slit longitudinally through the web by two cuts *b b*, thus affording a middle member *c* and two side members *d d*. Then by suitable dies the member *c* is bent away from the members *d d* in a direction at right angles to the web, and at the same time the members *d d* are bent together so as to compensate for the shortening of the metal caused by down-

bending of the member *c*. The usual fulcrum-piece *e* is then applied to connect and brace the members *c* and *d*, and this fulcrum-piece being riveted to both members *d d* ties them together, or they may be connected by a separate rivet-plate.

In Figs 2 and 3 I show the flanges of the members *d d* outwardly directed. In Fig. 4 they are inwardly directed toward the member *c*.

In Fig. 7 I show a modification in which the member *c* is flanged at its margin, the flanging being done simultaneously with the operation of bending it away from the members *d d*.

In Fig. 8 I show a modification in which the shortening of the metal piece occasioned by the downbending of the member *c* is compensated by also bending the members *d d* away from the member *c* instead of bending them laterally toward each other.

Within the scope of my invention many modifications may be made by those skilled in the art, since

What I claim is—

1. A brake-beam composed of a flanged piece cut through the web with longitudinal slits, the middle member and flanged side members thus constituted being separated in a direction transverse to the web; substantially as described.

2. A brake-beam composed of a flanged piece cut through the web with longitudinal slits, the middle member and flanged side members thus constituted being separated in a direction transverse to the web, the side members being bent to compensate for the shortening of the piece due to the bending of the middle member; substantially as described.

3. A brake-beam composed of a flanged piece cut through the web with longitudinal slits, the middle member and flanged side members thus constituted being separated in a direction transverse to the web, and the side members being bent toward each other; substantially as described.

4. A brake-beam composed of a flanged piece cut through the web with longitudinal slits, the

middle member and flanged side members thus constituted being separated in a direction transverse to the web, and the side members being bent toward each other and tied together; substantially as described.

5. A brake-beam composed of a flanged piece cut through the web with longitudinal slits, the middle member and flanged side members thus constituted being separated in a direction

transverse to the web, and the middle member ¹⁰ being flanged; substantially as described.

In testimony whereof I have hereunto set my hand February 18, 1904.

ETHAN I. DODDS.
